RAGNAR O. HEGGELUND AND HELMER I. SETBACKEN, OF LAKE PRESTON, SOUTH DAKOTA

CARBURETOR HEATER FOR AUTOMOBILES

Application filed August 12, 1929. Serial No. 385,116.

This invention relates to improvements in carburetor heaters for automobiles or for gasolene engines used in conjunction with a storage battery. One object is to provide a carburetor heater that can be applied exteriorly to the shell of the carburetor readily and without alteration of the same and as readily removed if desired. A further object is to provide a carburetor heater of few parts, simple in construction and that can be adjusted to deliver more or less heat as may be desired.

With the foregoing and other objects in view the invention consists in the combination and arrangement of parts to be hereinafter fully described, pointed out in the claims and illustrated in the accompanying drawing which forms a part of this application for patent and in which—

20 Fig. 1 is a view of a carburetor illustrating the application of the heater.

Fig. 2 is an enlarged fragmentary sectional view of Fig. 1.

Fig. 3 is a fragmentary side view of Fig. 2.

25 Fig. 4 is a top plan view of the heater element with the cover removed.

Like reference characters denote corresponding parts throughout the several views.

The carburetor heater comprises a vessel 30 having a body portion of insulation material and a cover of good heat-conducting material, the cover being placed against the base of the carburetor to heat the gasolene therein sufficiently to cause it to vaporize readily. This 35 vessel is adjustably secured to the carburetor shell by angular arms clamped to its sides and to the top of the shell.

The reference numeral 1 denotes a conventional type of carburetor. The heater 40 comprises a vessel having the body or container portion 2 made of insulation material and provided with the close fitting removable cover 3 of a heat conducting material, the base of said portion 2 being perforated to receive the binding posts 4, 5 to which the resistance coils 6, 7, 8 are secured, said posts having secured thereto also the leads 9, 10 that run to the storage battery (not shown).

45 The cover 3 is preferably of a size and shape to fit closely against the bottom of the

carburetor so that the heat generated in the vessel may be passed readily to the carburetor to heat the contents thereof. A collar 11 is formed with a flange 12 to receive and support the vessel body 2, said collar being of a 55 diameter and size to permit its engagement with the cover 3 and the shell of the carburetor. A pair of angular arms 13, 14, each of which is formed with an elongated slot 15, are adapted to be secured by screws 60 16 to the collar 11, the upper bent ends of said arms engaging with the top of the carburetor whereby to secure the heater to the carburetor. An adjustment of the collar and heater relative to the carburetor shell is possible by slightly loosening the screws 16 and after the desired adjustment is effected, tightening the screws again.

What is claimed is:—

1. In a carburetor heater, a vessel comprising a body portion of insulation material and a top of heat conducting material for application to the base of the carburetor, resistance coils within said vessel, a supporting collar for said vessel, and clamping means 70 for securing said collar to said vessel and the carburetor shell.

2. In a carburetor heater, a vessel comprising a body portion of insulation material and a top of heat conducting material for application to the base of the carburetor, resistance coils within said vessel, a supporting collar releasably connecting said vessel and the carburetor shell, angular longitudinally slotted arms for application to said collar 75 and carburetor shell, and screws for connecting the slotted portions of said arm and said collar.

3. In a carburetor heater, a vessel for application to the base of the carburetor, resistance coils within said vessel, a supporting collar for said vessel, and clamping means for securing said collar to said vessel and to the carburetor shell.

4. In a carburetor heater, a vessel comprising a body portion of insulation material and a top of heat conducting material for close fitting engagement with the base of the carburetor shell, resistance coils within said body portion, a flanged collar releasably en- 95

100

gaging the component members of said vessel and the carburetor shell, angular arms for connecting said collar and carburetor shell, and screws connecting said arms and collar.

5 In testimony that we claim the foregoing as our own we have hereto affixed our signatures.

HELMER I. SETBACKEN.
RAGNAR O. HEGGELUND.
